IMPELLER FOR WASHING MACHINES

John Whyte, Chicago, Ill., assignor to Electric Household Utilities Corporation, Chicago, Ill., a corporation of Illinois

Application January 23, 1937, Serial No. 121,922

5 Claims. (Cl. 68—131)

The present invention relates to washing machines for household use, and more particularly to a novel and improved impeller or agitator member employed in the tub of the washing machine for causing agitation of the water and clothes immersed therein. The present invention is directed to improvements for overcoming certain disadvantages and difficulties encountered in the use of certain well known types of 10 washing machines provided with impeller or agitator members.

In certain commercial types of washing machines the impeller or agitator member is mounted for rotation in a direction transverse to the vertical axis of the tub, and is disposed a substantial distance from the sides and bottom of said tub so as to permit free circulation of the washing fluid and clothes around and beneath the impeller member. In certain other 20 commercial constructions the impeller or agitator member is provided with a flanged base which is positioned in relatively close proximity to the bottom of the tub.

In washing machines of the type having the 25 impeller member mounted a substantial distance above the bottom of the tub it has been found that frequently clothing and other articles being washed become tangled and snagged by reason of the fact that forces acting on the water and on said articles have a tendency to move the clothes with the body of water, while at the same time a portion of the clothes may contact and have a tendency to cling to or wrap around the stationary supporting structure in the center of 30 the tub, which provides a support for the impeller member. This frequently results in several articles becoming intertwined, snagged and tangled, reducing the uniformity of washing.

In the other commercial form of washing machine above indicated, wherein the impeller member is mounted with its flanged base in close proximity to the bottom of the tub, it has been found necessary to frequently remove the impeller member from the tub for cleansing both 45 the bottom of the impeller member as well as the tub for removing accumulated residue, such as hardened soap matter, dirt, fibers and lint of the fabric that has been washed. At times this 50 accumulation beneath the impeller becomes so great that it impairs the operation thereof, and furthermore, sometimes this accumulation is such that if permitted to remain beneath the impeller, a portion of this matter may become loosened the next time the machine is used, re-

sulting in unnecessary contamination of the washing fluid.

In its broadest aspects the present invention is directed to the provision of an improved impeller member, preferably of unitary construction, including a substantial area disposed in a plane transverse to the vertical axis of the tub, and wherein the under side of said area is provided with a plurality of circumferentially spaced apart depending ribs or vanes which serve to 10 impel the washing fluid and clothes in an outward direction with respect to the vertical axis of the tub.

By the provision of the ribs or vanes beneath the impeller member in the respective commercial washing machine constructions above referred to, the above mentioned difficulties and disadvantages encountered are obviated.

Other features and advantages resulting from the present invention will be apparent from the 20 following description taken in connection with the accompanying drawings, in which:

Fig. 1 is a side elevation of an impeller member embodying the present invention.

Fig. 2 is a plan under side view of the impeller. 25

Fig. 3 is an enlarged vertical section through the washing machine showing the impeller member mounted in operative relation to the tub, together with driving means therefor.

For purpose of illustration I have selected a 30 washing machine construction of the type wherein the impeller or agitator member is mounted a substantial distance above the bottom of the tub. In the construction shown in the drawings reference character 10 designates a conventional form of tub, having associated therewith a supporting frame 11 which, together with the tub, are rigidly connected to supporting legs, not shown, for supporting the tub in proper spaced relation to the floor. The impeller member designated at 12 is mounted on a suitable support, herein shown as a hollow support 14, the upper portion of which is of frusto-conical form and the lower portion of said support being provided with a marginal annular flange 15, disposed beneath the tub and rigidly secured by bolts 16 to a flange 17 of a housing 18 disposed beneath the tub and carried on the frame 11. Interposed between said flange 15 of the support and the under surface of the tub bottom is a gasket 15a. 35 Mounted on the frame 11 is a prime mover, herein shown in the form of an electric motor 20, provided with a driving pulley 21 which through the medium of a V-belt 22 drives a pulley 23, which is operatively connected to suitable re- 40 45 50 55

versing mechanism enclosed within the housing 18 for transmitting movement to a vertically disposed drive shaft 24 which is journaled in a bearing 25 associated with said housing, and having its upper end protruding upwardly above the bottom of the tub, as seen in the drawings. It is to be understood that the mechanism enclosed within the housing 18 is such as to cause a definite amount of angular rotation of the shaft 24, alternately in opposite directions, and since said mechanism does not constitute any part of the present invention it is believed that a detail description and illustration thereof is unnecessary.

The bottom wall of the tub is provided with a relatively large aperture or opening 27 to permit the support 14 to be projected upwardly therethrough into the interior of the tub. To provide a seal for said aperture around the support 14, an annular threaded ring 28 is sweated onto the external lower portion of the housing 14, to be disposed above the bottom of the tub, on which ring is threaded a nut 29, adapted to engage a resilient sealing gasket 30 for tightly compressing same against the bottom of the tub surrounding the opening 27 and thereby provide a fluid-tight seal.

The upper end of the cone support 14 has rigidly secured, as by sweating inside the neck thereof, a reduced sleeve of an intermediate member 31 of a universal ball-and-socket joint. Said member 31 is provided interiorly and exteriorly with concentric spherical surfaces. Swivelly mounted on the exterior surface of the member 31 is a cooperating member 33, the inner surface of which corresponds exactly to the outer surface of the member 31, and formed integrally with said member 33 is an upstanding hub portion 34 which is rigidly secured by means of a pin 35 to an impeller shaft 36 which extends downwardly through the member 31 and is supported by the member 33 seated upon the member 31. The impeller shaft is disposed at an angle to the vertical axis of the drive shaft 24, with the lower portion thereof extending downwardly and interiorly of the hollow support 14. Mounted on the upper end of the impeller shaft 36 is the impeller member 12, disposed in a plane normal to the axis of the impeller shaft.

The impeller shaft 36 is held against axial movement in the ball-and-socket members 31 and 33 by the construction now to be described. A collar 38 is rigidly secured to the lower end of the shaft 36 by a pin 39 and reacting between said collar and a sleeve 40 is a compression spring 41 which urges the upper end of the sleeve 40 upwardly against a cooperating internal member 42 of the universal joint. Said member 42 is of hollow semi-spherical form and having its external surface corresponding to and swivelly engaging the internal surface of the intermediate universal member 31, and provided with an aperture 42* through which the impeller shaft extends. The extreme lower end of the impeller shaft 36 extends through an aperture 45 in the outer end of a laterally extending inclined arm 46 of a crank member 47 which is rigidly secured by means of the pin 48 to the upper end of the drive shaft 24.

As the drive shaft 24 is rotated it will be manifest that due to the crank arm being connected to the impeller shaft 36, said impeller shaft will be rotated in an orbit around the axis of the drive shaft, and thereby imparting corresponding movement to the impeller member 12. To accommodate such movement, the inner member 31 of the universal joint is provided with an open-

ing 31* at its upper end to provide clearance for the impeller shaft in its travel in said orbit about the axis of the drive shaft 24.

The impeller member 12 preferably is in the form of a unitary casting, and as shown includes a laterally extending marginal flange portion 12* of substantially circular outline, formed with a series of hills and valleys to provide a sinuous contour to both upper and lower surfaces of the flanged portion 12*. Said flanged portion merges into an upwardly extending irregular shaped dome 12*, the upper portion of which is provided with a boss 12* in which is disposed a spring-pressed detent 50 carried by a screw bushing 51, the detent engaging in an aligned annular groove 36* in the impeller shaft 36 for detachably securing the impeller member in position on said shaft. Mounted on the upper end of said dome portion of the impeller is an annular ring 52 secured in place on the shoulder formed at the upper end of said dome by means of a cap 54, the marginal edges of which are crimped into an annular groove 12* formed in the upper end of the dome of the impeller with the lower edges of said cap engaging the annular ring 52 for holding it in fixed position. Said ring 52 serves as a convenient hand-grasp for bodily removing the impeller member from the impeller shaft. Formed centrally on the under side of the impeller member is an integral, inverted frusto-conical skirt 12*, the lower portion of which is adapted to extend around and slightly below the lower edge of the outer universal joint member 33, out of contact therewith.

Formed on the under side of the flanged portion 12* and the dome of the impeller member are a plurality of circumferentially spaced-apart radially extending ribs or vanes 12* which extend continuously from adjacent the outer marginal edge of said flanged portion and merge into the inclined surface of said skirt 12*. These vanes serve as impeller members so that when the impeller is rotated about the vertical axis of the drive shaft 24 the washing fluid and clothes immersed therein are impelled in an outward direction, and the currents of fluid being continuously set up by the movement of the impeller member tends to constantly move clothing or other articles being washed, in an outward direction away from the hollow support 14. It has been found from actual experiment that this construction practically eliminates entirely tangling and snagging of articles being washed.

From the foregoing it is believed to be obvious that the use of vanes or ribs on the under side of the impeller or agitator member of the type having a flanged base disposed in close proximity to the bottom of the tub will have a definite tendency to prevent accumulation of deposits of residue and foreign matter beneath the impeller member so as to render it substantially unnecessary to remove said impeller for the purpose of cleansing the same, as well as the bottom of the tub. It is therefore believed that illustration and a detail description of this type of washing machine is unnecessary.

Although I have herein shown and described one embodiment of my invention, manifestly it is capable of modification and rearrangement without departing from the spirit and scope thereof. I do not, therefore, wish to be understood as limiting the invention to the precise embodiment herein disclosed, except as it may be so limited in the appended claims.

I claim:

1. In a washing machine, in combination with a tub adapted to contain the washing fluid and clothes to be washed, an impeller member positioned centrally within the tub at an angle to the vertical axis of the tub, and movable bodily in an orbit about said axis of the tub, said impeller being mounted for free rotation about its own axis and spaced annularly from the side wall of the tub and located above the bottom wall thereof a sufficient distance to provide space for the free movement of the clothes and fluid around and beneath the impeller member, said impeller member being of unitary formation including a substantially continuous area extending transversely of the vertical axis of the tub, and a plurality of circumferentially spaced apart depending ribs formed integrally with and projecting perpendicularly from the under side of said area and extending continuously from adjacent the outer marginal edge of said area and terminating adjacent the center thereof. 5
- 10
5. In a washing machine, in combination with a tub adapted to contain the washing fluid and clothes to be washed, an impeller member positioned centrally within the tub at an angle to the vertical axis of the tub and movable bodily in an orbit about said axis of the tub and being freely rotatable about its own axis, said impeller being spaced annularly from the side wall of the tub and located above the bottom wall thereof a sufficient distance to provide space for the free movement of the clothes and fluid around and beneath the impeller member, said impeller member being of unitary formation including a substantially continuous area extending transversely of the vertical axis of the tub, an inverted frusto-conical skirt formed integrally with the under side and substantially centrally of said area of the impeller member, and a plurality of circumferentially spaced apart depending ribs formed integrally with the under side of said area and extending continuously from adjacent the outer marginal edge of said area and terminating adjacent said skirt. 15
- 20
4. In a washing machine, in combination with a tub adapted to contain the washing fluid and clothes to be washed, a vertical drive shaft having a portion extending upwardly through the bottom of the tub, a crank arm carried on said portion of the drive shaft, and means for rotating said shaft and arm; of an impeller member connected to the outer member of said arm, said impeller member being positioned with its axis disposed obliquely to the angle of the drive shaft and adapted to be bodily revolved with said arm in an orbit about the axis of said drive shaft and being freely rotatable about its own axis, said impeller member being of unitary formation including a substantially continuous area extending in a plane at an angle to the axis of said shaft, and a plurality of circumferentially spaced apart depending ribs formed integrally with and projecting perpendicularly from the under side of said area and extending continuously from adjacent the outer marginal edge of said area and terminating adjacent the center thereof. 25
- 30
3. In a washing machine, the combination with a tub adapted to contain the washing fluid and clothes to be washed, a vertical drive shaft having a portion extending upwardly through the bottom of the tub, a crank arm carried on said portion of the drive shaft, an upwardly extending impeller shaft connected to the outer end of the crank arm and disposed with its axis at an angle to the axis of the drive shaft, means for rotating said drive shaft and arm; of an impeller member mounted for free rotation on the impeller shaft and including a substantially continuous area disposed in a plane at substantially right angles to 35
- 40
5. In a washing machine, in combination with a tub adapted to contain the washing fluid and clothes to be washed, an impeller member positioned centrally within the tub at an angle to the vertical axis of the tub and movable bodily in an orbit about said axis of the tub and being freely rotatable about its own axis, said impeller being spaced annularly from the side wall of the tub and located above the bottom wall thereof a sufficient distance to provide space for the free movement of the clothes and fluid around and beneath the impeller member, said impeller member being of unitary formation including a substantially continuous area extending transversely of the vertical axis of the tub, an inverted frusto-conical skirt formed integrally with the under side and substantially centrally of said area of the impeller member, and a plurality of radially extending circumferentially spaced apart depending ribs formed integrally with the under side of said area and extending continuously from adjacent the outer marginal edge of said area and terminating adjacent said skirt. 45
